(57) **CLAIM**

We claim the ornamental design for a pipe having a spigot end and a bell end, as shown and described.

DESCRIPTION

FIG. 1 is a front perspective view showing our new design;

FIG. 2 is a side elevational view of the design;

FIG. 3 is a front elevational view thereof; and,

FIG. 4 is a rear elevational view thereof.

The design is shown broken away in order to indicate that a specific length of pipe forms no part of the claimed design.
